UNITED STATES PATENT OFFICE.

NORMAN P. HARSHBERGER, OF CHICAGO, ILLINOIS.

SHINGLE.

Application filed June 19, 1925. Serial No. 38,925.

This invention relates to shingles and particularly shingles which are composed of flexible composite sheets. One of the objects of the invention is to provide means for locking down the exposed or lap portions of the shingles so as to prevent this portion from warping or being blown upwardly and thus causing a tendency to leak and also affecting undesirably the appearance of the roof. Another object of the invention is to provide shingles shaped so as to expedite the laying of the shingles on the roof.

Of the accompanying drawings Fig. 1 is a plan view of a plurality of shingles, as they appear when assembled, embodying features of my invention; Fig. 2 is a bottom view of several assembled shingles; and Fig. 3 is a plan view of a single shingle as it is cut and formed from the sheet.

In forming roof coverings with shingles it is desirable to provide a pleasing appearance for the roof and to accomplish this consideration must be given to the appearance of the shingles after they are laid rather than to the appearance of the individual shingles; and the shingles should be made and laid so as to maintain this pleasing appearance against the inroads of rain, wind, age, sunlight, and so on. While the general shape of the shingles which I have invented may be modified more or less, yet I prefer shingles that will produce, when laid, substantially a square or diamond-shaped figure and particularly one which approaches a hexagon, having some of its corners eliminated by straight edges. I also prefer to have the corners instead of the edges extending longitudinally and transversely of the roof, as indicated in Fig. 1.

This appearance is arrived at by laying the shingles with one corner extending downwardly; and at the same time the exposed or lap portion of the shingle may be locked down by turning this corner under an underlying shingle. But provision must be made for edges under which this corner may be turned and also care must be taken to prevent leakage. I provide for these various features in the following manner:

The individual shingle comprise a body 22 which has the general shape of a parallelogram, or diamond, preferably a square. These shingles when assembled are laid in horizontal rows with the adjacent corners

11 substantially in contact. In order to prevent leakage the shingles of each row are staggered with reference to the shingles of the adjacent rows and the shingles of the 60 upper rows over-lap the adjacent edges of the under rows so much as may be deemed desirable. That is the edges 25 of a shingle in one row over-lap the edges 13 of the two adjacent shingles in the next lower row. In 65 order to lock down the exposed portion of each shingle the lower corner 24 is folded under the shingle and this corner is slipped under the edges 25 of the two adjacent under-lying shingles. In order to accomplish 70 this in an effective and easy manner I form offsets or shoulders 21 in the edges 25 of the under-lying shingles and the corner 24 passes under the two adjacent edges 21 as indicated. In this manner the laps are 75 permanently locked down and leakage is avoided by the over-lapping of the upper shingles on the lower shingles.

By this arrangement also a pleasing diamond-shaped figure is produced, but with 80 edges 18 instead of corners. And as these edges are formed by the turning of the corners, and with the shoulder 21 enclosed between the corners and the body of the shingles, a thick prominent edge 18 is formed 85 which adds materially to the appearance of the roof, emphasizing the particular figure formed. This turning under of the corners also emphasizes somewhat the edges 25 so that the entire figure is more prominent. 90

The shingles may be cut from sheets in any ordinary or usual manner.

The shoulders 21 are formed by cutting in the square- or diamond-shaped shingle a slit along the edge of the body portion 22 95 and turning under the strip 23. In other words, the strips 23 and a corner 24 are all turned under the shingle. In this manner the shoulders 21 are formed. And in assembling these shingles on the roof, not only is 100 the corner 24 turned under the shoulders 21 of the underlying shingles, but the strips 23 are positioned between the shingle to which they are attached and the under-lying shingle, so as to make a much more 105 definite edge 25, thus emphasizing still more the figures which are formed by the roof. At the same time the strips 23 tend to elevate the shoulders 21, when the shingles are laid on the roof, so that the corners 24 are 110 more readily slipped under the shoulders.

In laying these shingles it is necessary

only to true up the lower row and the shingles of the next row will be properly positioned as soon as the corner 24 is placed under the proper shoulders 21. But in order to insure the proper position of the shingles it is desirable also to see that the corners 11 register with the adjacent similar corners. In this manner the shingles may be laid truly over the entire roof without any additional means being used. And by having the shoulders 21 elevated as explained the laying of the shingles is a simple and rapid process.

I claim as my invention:

15 A shingle made from flexible composite

shingle material having a body portion, the periphery of which forms substantially a parallelogram but the two adjacent edges thereof having offset portions, and the corner formed by said edges being folded under the body portion of the shingle, the fold thereof forming a straight edge, forming substantially equal angles with the two adjacent sides, each of said edges having a strip integral therewith and also folded under the body portion of the shingle. 20 25

In testimony whereof, I hereunto set my hand.

NORMAN P. HARSHBERGER.
